UNITED STATES PATENT OFFICE

2,512,488

SPINNERET AND MOUNTING THEREFOR

Robert Hème de Lacotte and Eugène Colombu,
Paris, France, assignors to Societe de Construc-
tions Mecaniques de Stains, a corporation of
France

Application June 2, 1947, Serial No. 751,949
In France June 15, 1942

Section 1, Public Law 690, August 8, 1946
Patent expires June 15, 1962

2 Claims. (Cl. 18—8)

1

This invention relates to apparatus for producing artificial textiles. More particularly, it relates to new and improved spinnerettes and the mounting thereof in spinning machines for producing artificial textiles.

In the manufacture of artificial textiles, the spinning solution is fed through pipelines from the tanks in which it has been stored to a distributing pipe running the length of the spinning machine. From this feed line, manifold lateral branches lead to the spinning pumps which deliver a constant and unvarying amount of solution through the spinnerettes per unit of time. Normally, the pumps force the solution through a filter, from which the solution passes through a glass tube, commonly termed a "gooseneck," and thence through the spinnerette.

The spinnerettes can be made of any appropriate material, such as metal, glass, plastic, or the like. In the viscose industry, metal spinnerettes and especially spinnerettes formed of platinum, platinum alloys or other precious metals are almost exclusively used.

In general, the spinnerette consisted of a small perforated plate having an annular depending skirt which was provided at the bottom thereof with an annular, outwardly extending flange. In use, the bottom flange of the spinnerette was positioned on the top of an exteriorly threaded support (male member) appropriately secured to the gooseneck and was secured in position by a flange at the top of a nut (female member) which threadededly cooperated with the male member.

The above-mentioned mode of mounting the spinnerette was, in general, satisfactory for the spinning of rayon where the number of orifices was comparatively small and sufficiently spaced. However, in the spinning of fibranne (staple), spinnerettes having several thousand orifices, such as, for example, 5000 to 10,000 or even more, are used. Naturally, such spinnerettes are of greater dimensions but, in order to utilize them to a maximum, it is necessary that the orifices extend almost to the edge of the skirt. In fact, it has been indicated to limit the surface in order to save metal and also to avoid any bulging produced under the effect of the repelling pressure of the spinning solution. The more the surface is limited, the less is the risk of bulging. Additionally, the orifices must not be too close to one another. They must be sufficiently spaced so that the coagulating liquid will be able to penetrate sufficiently between the jets of spinning solution extruded from the orifices.

2

An object of this invention is to provide a new and improved spinnerette.

Another object of this invention is to provide a more economical spinnerette.

5 A further object of this invention is to provide a new and improved means for mounting the spinnerettes in position on the gooseneck.

Other and additional objects will become apparent hereinafter.

10 The objects of the invention are accomplished, in general, by making a spinnerette in the form of a perforated plate having an annular depending skirt and disposing said skirt on an exteriorly threaded portion of a holder which, in turn, is removably (threadedly) secured adjacent the bottom thereof onto a support appropriately secured to the gooseneck. A locking ring, which binds the skirt to the threads of the holder, secures the spinnerette in position on the holder.

15 20 The holder and support are hollow, and the holder together with the spinnerette mounted thereon can be removed from the support as a single unit. When desired, the holder is also provided with means whereby a protective cap

25 can be removably secured thereto when the spinnerette mounted on the holder is not in use, such as after the spinnerette has been cleaned.

The present invention will be more clearly understood by reference to the following detailed description when taken in connection with the accompanying drawings, in which:

Figure 1 is an elevation, partly in section, showing the spinnerette and the manner in which it is mounted; and

35 Figure 2 is a section of the protective covering.

Referring now to the drawings wherein like reference numerals designate like parts, the reference numeral 1 designates a tube (gooseneck) through which the spinning solution is

40 passed and which is provided with an annular flange 2 at the top thereof. The flange 2 is secured by any appropriate means to a flange 3 at the bottom of a support 4, which is threaded on the exterior surface thereof, as indicated by the reference numeral 5. A spinnerette holder

45 45 is interiorly threaded adjacent the bottom thereof whereby it is threadedly secured on the support 4. The holder 9 is provided with spurs 10 and 11 and a milled surface 12, for reasons

50 which will hereafter appear. The spinnerette holder 9 is formed at the top thereof with an extension 13 which is threaded on the exterior surface thereof, as indicated by the reference numeral 15.

55 As shown in Figure 1, the spinnerette, gen-

erally indicated by the reference numeral 14, is provided with a multiplicity of spaced orifices 20 and an annular depending skirt 21. The depending skirt 21 of the spinnerette 14 is disposed on the threaded portion 15 of the extension 13. A locking ring 16 cooperating with the skirt 21 causes the metal of the skirt 21 to bind with the threads 15 whereby its immobility and the tightness of the joint are insured. A shoulder 22 limits the downward movement of the locking ring 16 when it is applied.

The inner surface of the extension 13 flares outwardly in the direction toward the spinnerette so that the spinning solution will be fed to all of the orifices including those adjacent the skirt.

The holder 9 is provided with a second shoulder 23 which cooperates with the top of the support 4.

When for any reason the spinnerette has to be replaced, such as when it becomes clogged, the spinnerette holder 9 is gripped at the milled portion 12 and manually manipulated so as to unscrew it together with the spinnerette locked in position thereon from the support 4. After removal, another assembly of the spinnerette holder with the spinnerette secured in position thereon is screwed into position on the support 4.

The spinnerette can be cleaned while it is mounted on the support. Generally, after a spinnerette is cleaned, it is not immediately restored to use. Since the spinnerette orifices must be kept clean, the instant invention provides means, such as a protective cap 17, which is removably secured on the assembly, as will now be explained.

The protective cap 17 is preferably made of any suitable material, such as aluminum, and of the form and shape generally shown in Figure 2. The cap 17 is formed with a shoulder 18, which is adapted to seat on the locking ring 16. The inner diameter of the top of the cap above the shoulder 18 is substantially the same as the top of the spinnerette, and the diameter of the skirt of the cap below the shoulder is such that it can be disposed on the holder 9. The peripheral wall of the cap 17 is provided with a pair of oppositely disposed bayonet slots 19, designed to cooperate with the spurs 10 and 11 of the holder 9. In position, the protecting cap 17 is secured on the outside of the holder 9 and protects the spinnerette so that no access thereto can be had by dirt, and particularly dust. When the assembly is desired to be used, the protective cap 17 is removed.

As is apparent from the foregoing description, the skirt of the spinnerette is bound to the threads 15 of the extension 13. This requires the skirt to be made of a sufficient thickness to withstand such action. The increase in the metal required by this is minor compared to the fact that the spinnerette does not require, and is therefore not formed with, a bottom outwardly extending flange as was necessary with the prior art spinnerettes. The support and holder can be made of any appropriate material, such as metal, for example Monel metal, or of plastic. Preferably, the holder 9 is made of metal.

The invention provides a spinnerette which does not have a bottom flange, which characterized the prior art spinnerettes. As a consequence, there is a considerable saving of material of which the spinnerette is made. When the spinnerette

is made of platinum or platinum alloys, the saving is of considerable value.

Due to the method of mounting the spinnerette, the holder and spinnerette can be removed from and quickly replaced as a single unit on the support carried by the gooseneck.

Since it is obvious that various changes and modifications can be made in the above description without departing from the nature or spirit thereof, this invention is not restricted thereto except as set forth in the appended claims.

We claim:

1. In a spinning apparatus, a feed tube for the spinning solution, an annular support attached to the end of said tube, an annular spinnerette holder threaded onto said support and having an internal shoulder engaging the end of said support for positioning said holder, said holder having an inwardly offset, upwardly extending flange forming an external shoulder, a spinnerette comprising a plate formed of a metal selected from the group consisting of platinum and platinum alloys, said plate being disposed over the end of said flange and having a flat top wall provided with a plurality of holes for the extrusion of the spinning solution, a depending skirt threaded onto said flange above said external shoulder, a clamping ring disposed around said skirt exerting pressure to clamp the same to said flange, said clamping ring being substantially flush with the exterior surface of said holder below said external shoulder, and a removable closure cap having a depending skirt extending over said ring and said holder and removably secured to said holder.

2. In a spinning apparatus having a feed tube for the spinning solution, a spinnerette comprising a plate formed of a metal selected from the group consisting of platinum and platinum alloys, said plate having a flat top wall provided with a plurality of holes for the extrusion of the spinning solution and a depending interiorly threaded unflanged skirt, a hollow spinnerette holder having an externally threaded extension adjacent the top thereof on which said skirt is screwed and a clamping ring disposed around the skirt and exerting pressure to bind said skirt with the threads on said extension, said holder being interiorly threaded adjacent the bottom thereof, and a support carried by said tube and having external threads on which said holder is screwed whereby said holder can be removably secured to said support.
